(57) **CLAIM**

The ornamental design for a linear luminaire with continuous lens, as shown and described.

DESCRIPTION

FIG. 1 is a bottom perspective view of a linear luminaire with continuous lens, showing our new design;

FIG. 2 is a top perspective view thereof;

FIG. 3 is a top plan view thereof;

FIG. 4 is a bottom plan view thereof;

FIG. 5 is a side view thereof;

FIG. 6 is another side view thereof;

FIG. 7 is an end view thereof; and,

FIG. 8 is another end view thereof.

The broken lines shown in the figures illustrate portions of the linear luminaire with continuous lens that form no part of the claimed design. The break lines in the drawings indicate that the appearance of any portion of the linear luminaire between the break lines forms no part of the claimed design.
